UNITED STATES PATENT OFFICE

ALONZO ALDRICH, OF BELOIT, WISCONSIN

SHAKING MECHANISM FOR FOURDRINIER MACHINES

Application filed July 2, 1923. Serial No. 648,962.

My invention relates to Fourdrinier paper making machines, and particularly to shaking mechanism therefor.

One of the objects of the invention is to provide a simple, practical and advantageous construction of Fourdrinier machine capable of being shaken and of shaking mechanism therefor.

Another object of the invention is to avoid vibration as a result of the operation of the shaking mechanism.

Another object of the invention is to provide a shaking mechanism which shall be especially adapted to cooperate with a Fourdrinier machine having a table made laterally removable to permit application of a new wire and also having a table vertically adjustable at its feed end to control character of fiber.

Other objects of the invention will appear and be pointed out hereinafter.

In the accompanying drawings Fig. 1 is a plan of the table of a Fourdrinier machine and shaking mechanism therefor, embodying my present invention;

Figs. 2 and 3 are cross-sections taken on line 2—2 and 3—3, respectively, in Fig. 1 on an enlarged scale;

Fig. 4 is a plan view of the mechanism shown in Fig. 3;

Fig. 5 is an end elevation of the feed end portion of the table;

Fig. 6 is a view taken on line 6—6 in Fig. 3; Fig. 7 is a section on line 7—7 in Fig. 2;

Fig. 8 is a view of a detail of construction; Fig. 9 is a section on line 9—9 in Fig. 1; and Fig. 10 is a section on line 10—10 in Fig. 9.

Referring to the drawings, I show the table section 1 of a Fourdrinier machine having rolls 2—2 and a shaking mechanism at the rear thereof, as shown in Fig. 1.

This shaking mechanism comprises a series (four are shown in Fig. 1) of upwardly extending reciprocating or vibratory members 43—43 mounted on rock shaft 44, which is supported by bearings 45—45 located on the floor, whereby shaft 44 is low and vibration is prevented. Upright members 43 are connected with table section 1 by detachable connections permitting table to be shaken as de-

sired, and also permitting detachment or disconnection of shaking mechanism to allow removal of table in direction away from such mechanism for applying new wire.

The connections between the two middle members 43 and table are shown in Figs. 2 and 7. They comprise straps 51 connected to yokes 52 which are on opposite sides of uprights 43, yoke members 52^a sliding between rolls 53—53 on boxes 54 which enclose uprights 43 and are also connected with straps 51. Boxes 54 are provided with openable sides 55 normally held in position so as to engage upright 43 by bolt 56 and hand nut 57. By unscrewing the latter, side 55 may be swung about pivot bolt 58 so as to open box 54 and allow separation of same from upright 43. The connection for the right hand end member 43 is shown in Figs. 9 and 10. It comprises a strap 51, such as previously described, but same has a pivotal connection 59 with the jointed section 1^b of the table, and also a connection 60 with the shaking section 1 of the table, whereby both sections are shaken. The connection for the left hand-most member 43 is shown in Figs. 3 and 4. It comprises a box 61, open at one side and having an inclined side and a connection 63 for the brest roll bearing 64. Section 1 of table is mounted on flexible members 41 whose lower ends are secured to channel members 42, to permit shaking of rolls 2 and wire thereon without shaking the remainder of the table.

Vibratory members 43 are actuated by rocking of shaft 44 by vertically vibrating arms 47 actuated by reciprocating members 47^a controlled by shaft 47^b which is turned by gear connection with power shaft 48, so that rotation of latter will vibrate members 43 and so shake table.

Thus the whole table section 1 and brest roll also may be shaken as desired and also detached from shaking mechanism to permit removal of table for applying new wire, as shown in Figs. 2 and 3.

Certain subject matter of this application is disclosed and claimed broadly in my pending applications, Serial No. 595,258, filed October 18, 1922; Nos. 648,959, 648,960, 100

648,961, filed July 2, 1923, and No. 205,006, filed July 11, 1927.

It will be understood that changes and modifications may be made without departing from the spirit of the invention.

5. What I claim is:

1. Shaking means for a Fourdrinier machine comprising means for imparting a vibratory motion to the machine table and adapted to permit the lateral removal of the portion of the table which is shaken and the vertical adjustment of the same.
10. Shaking means for a Fourdrinier machine comprising vibratory mechanism and means for connecting same with a machine table so as to shake same and also to permit the bodily lateral removal of the portion of the table which is shaken and the vertical adjustment of the same.
15. Shaking means for a Fourdrinier machine comprising an actuating member mounted upon and close to the floor on which the machine is mounted and provided with upwardly extending members which are adapted for connection with the machine table for shaking the same, means for operating said actuating member and vertically adjustable connections on said upwardly extending members.
20. 3. Shaking means for a Fourdrinier machine comprising vibratory mechanism for vibratory member mounted upon and located near the floor on which the machine is mounted and upwardly extending members carried by said vibratory member and arranged for connection with the machine table, a horizontally arranged member extending horizontally from said vibratory member, means for actuating said horizontally extending member so as to vibrate said vibratory member and vertically adjustable connections on said upwardly extending members.
25. 4. Shaking means for a Fourdrinier machine comprising vibratory mechanism for vibratory member mounted upon and located near the floor on which the machine is mounted and upwardly extending members carried by said vibratory member and arranged for connection with the machine table, a horizontally arranged member extending horizontally from said vibratory member, means for actuating said horizontally extending member so as to vibrate said vibratory member and vertically adjustable connections on said upwardly extending members.
30. 5. Shaking means for a Fourdrinier machine comprising a vibratory shaft mounted upon and arranged close to the floor on which the machine is mounted and having upwardly extending vibratory members for connection with and vibration of the machine table, a horizontally extending member extending laterally from said vibratory shaft, means for vibrating said horizontally extending member and vertically adjustable connections on said upwardly extending members.
35. 6. Shaking means for a Fourdrinier machine comprising swinging, vibratory members and boxes enclosing said swinging vibratory members and removable from the same.
40. 7. Shaking means for a Fourdrinier machine comprising swinging, vibratory members and boxes enclosing said swinging vibratory members and removable from the same, said boxes having a removable side pivoted in position and locking means for temporarily holding the same in position.

8. Shaking means for a Fourdrinier machine comprising vibratory members and boxes enclosing said vibratory members and removable from the same, said boxes having a removable side pivoted in position and locking means for temporarily holding the same in position, and a sliding yoke having its side members on opposite sides of said box.

9. Shaking means for a Fourdrinier machine comprising vibratory members and boxes enclosing said vibratory members and removable from the same, said boxes having a removable side pivoted in position and locking means for temporarily holding the same in position, and a sliding yoke having its side members on opposite sides of said box, the table being mounted on flexible members.

10. Shaking means for a Fourdrinier machine comprising vertically arranged vibratory members carrying vertically adjustable connecting devices which latter are adapted for free vertical adjustment on said vertical members and are provided with means for holding them in various vertically adjusted positions.

11. Shaking means for a Fourdrinier machine comprising means for vibrating the table, and also for shaking the brest roll, said means comprising vibratory members to engage the table portions and brest roll and mechanism for actuating said vibratory members in unison, said mechanism comprising a rock shaft supporting the vibratory members and means for vibrating the rock shaft.

12. Shaking means for a Fourdrinier machine comprising means for vibrating the table, and also for shaking the brest roll, said means comprising vibratory members to engage the table portions and brest roll and mechanism for actuating said vibratory members in unison, said mechanism comprising a rock shaft supporting the vibratory members and means for vibrating the rock shaft, said means comprising eccentric members.

13. Shaking means for a Fourdrinier machine comprising means for vibrating the table, and also for shaking the brest roll, said means comprising vibratory members to engage the table portions and brest roll and mechanism for actuating said vibratory members in unison, said mechanism comprising a rock shaft supporting the vibratory members and means for vibrating the rock shaft, said means comprising eccentric members and a power generator for driving said eccentric mechanism.

14. Shaking means for a Fourdrinier machine comprising a vibratory member and a detachable connection therefor consisting of a box adapted to enclose the vibratory member and having a removable side provided

- with means for temporarily locking said side in position.
15. Shaking means for a Fourdrinier machine comprising a vibratory member and a detachable connection therefor consisting of a box adapted to enclose the vibratory member and having a removable side provided with means for temporarily locking said side in position, said side being pivotally mounted and held in position by a threaded bolt and nut therefor and said connection having a yoke portion, the parts of which extend on opposite sides of the box which latter is provided with rollers for said yoke portion.
16. Shaking means for a Fourdrinier machine comprising upwardly extending vibratory members and means at the lower ends of said members for vibrating the same, in combination with detachable connections for the vibratory members and means for holding said connections in position.
17. Shaking means for a Fourdrinier machine comprising a vibratory member and a table connection thereon, said connection being adapted for detachment from and adjustment relatively to said vibratory member.
18. Shaking means for a Fourdrinier machine comprising a swinging vibratory member and a table connection therefor adapted for disconnection from said vibratory member and also for longitudinal adjustment thereon.
19. Shaking means for a Fourdrinier machine comprising a vibratory member and a table connection thereon and means for holding said table connection in position comprising an enclosing structure, one side of which is a pivoted member having a temporary fastening device.
20. Shaking means for a Fourdrinier machine comprising a vibratory member, a table connection thereon and a flexible member for attaching said table connection to the table.
21. Shaking means for a Fourdrinier machine comprising a vibratory member, a detachable table connection thereon and an anti-friction device for taking up vibration.
22. Shaking means for a Fourdrinier machine comprising a vibratory member, a detachable table connection thereon and an anti-friction device for taking up vibration, and a flexible member adapted to form a flexible connection between said table connection and the table.
23. Shaking means for a Fourdrinier machine comprising a longitudinally arranged vibratory member and table connection arranged on said member and adapted for longitudinal adjustment on said member and a table connector having means for connection with the table and anti-friction devices on said table connection for cooperation with said connector.
24. Shaking means for a Fourdrinier ma-
- chine comprising a longitudinally arranged vibratory member and table connection arranged on said member and adapted for longitudinal adjustment on said member and a table connector provided with means for connection with the table at a plurality of points, and anti-friction devices on said table connection for cooperation with said connector.
25. Shaking means for a Fourdrinier machine comprising an upwardly extending vibratory member, a table connection thereon and a flexible member carried by said table connection and adapted for connection with the table.
26. Shaking means for a Fourdrinier machine comprising an upwardly extending vibratory member, a table connection thereon, a table connector adapted for securement to vibratory members of the table and having a loose anti-friction connection with said table connection and a flexible member connected with said table connector and also with said table connection on the vibratory member.
27. Shaking means for a Fourdrinier machine comprising a substantially vertically arranged vibratory member, an adjustable device thereon arranged for longitudinal adjustment of said member, a table connector adapted for securement to a shakable member of the table and having loose-holding connection with said adjustable device and a flexible member having one end connected to said adjustable device and the other end connected to said table connector.
28. Shaking means for a Fourdrinier machine comprising a substantially vertically arranged vibratory member, an adjustable device thereon arranged for longitudinal adjustment of said member, a table connector adapted for securement to a shakable member of the table and having loose-holding connection with said adjustable device and a flexible member having one end connected to said adjustable device and the other end connected to said table connector, said adjustable device being detachable from said vibratory member and said table connector being detachable from said adjustable device.
29. The combination of a Fourdrinier machine having a laterally removable, shakable and vertically adjustable table and shaking means having vibratory members connected with the table by connections carried by the table and adapted to be vertically adjusted upon and detached from said vibratory members.
30. The combination of a detachable vertically adjustable and shakable table of shaking mechanism having vibratory members provided with vertically adjustable connection with the table.
31. The combination of a detachable table and shaking mechanism having swinging

- vibratory members provided with means for connection with and disconnection from the table, said means including connecting devices enclosing said swinging vibratory members and separable therefrom.
- 5 32. The combination with a detachable table of shaking mechanism comprising swinging vibratory members provided with means for connection with and disconnection from the table, said means comprising boxes enclosing said swinging vibratory members and provided with removable portions to permit disconnection of boxes from the vibratory members.
- 10 33. The combination with a detachable table of shaking mechanism comprising swinging vibratory members provided with means for connection with and disconnection from the table, said means comprising boxes enclosing said swinging vibratory members and provided with means for adjustment thereon.
- 15 34. The combination with a detachable table of shaking mechanism comprising swinging vibratory members provided with means for connection with and disconnection from the table, said means comprising boxes enclosing said swinging vibratory members and also adapted to permit adjustment relatively to said members.
- 20 35. A Fourdrinier machine having a laterally removable table, means for removing the same, and shaking means comprising vibratory members adapted to be connected to and disconnected from the table, said disconnecting means comprising boxes fitted over said vibratory members and having removable sides and means for temporarily fastening said sides in position and straps connected with said boxes and also with the table.
- 25 36. A Fourdrinier machine having a laterally removable table provided with laterally removable shaking members, means for removing the same, and shaking means comprising vibratory members adapted to be connected to and disconnected from the table, said disconnecting means comprising boxes fitted over said vibratory members and having removable sides and means for temporarily fastening said sides in position and straps connected with said boxes and also with the table, said straps being connected to the shakeable members of the table.
- 30 37. A Fourdrinier machine having a laterally removable table provided with laterally removable shaking members, means for removing the same, and shaking means comprising vibratory members adapted to be connected to and disconnected from the table, said disconnecting means comprising boxes fitted over said vibratory members and having removable sides and means for temporarily fastening said sides in position and straps connected with said boxes and also with the table, said straps being connected to the shakeable members of the table, the shakeable
- members of the table being mounted on flexible members.
38. A Fourdrinier machine having a laterally removable table, provided with laterally removable shaking members, means for removing the same, and shaking means comprising vibratory members adapted to be connected to and disconnected from the table, said disconnecting means comprising boxes fitted over said vibratory members and having removable sides and means for temporarily fastening said sides in position and straps connected with said boxes and also with the table, said straps being connected to the shakeable members of the table, the shakeable members of the table being mounted on flexible members, and means for vibrating said vibratory members comprising a rock shaft and power means for rocking the same.
- 70 39. A Fourdrinier machine having a laterally removable table, provided with laterally removable shaking members, means for removing the same, and shaking means comprising vibratory members adapted to be connected to and disconnected from the table, said disconnecting means comprising boxes fitted over said vibratory members and having removable sides and means for temporarily fastening said sides in position and straps connected with said boxes and also with the table, said straps being connected to the shakeable members of the table, the shakeable members of the table being mounted on flexible members, and means for vibrating said vibratory members comprising a rock shaft and power means for rocking the same.
- 75 40. The combination with a table having shake members, of a shake connection therefor involving a vertically arranged swinging member and a readily detachable connection mounted on said member, and a flexible connection between said connection and shake member.
- 80 41. In witness whereof, I hereunto subscribe my name this 26th day of May, A. D. 1923.
